Robert H. Howard

UNITED STATES PATENT OFFICE.

FRED R. AKERLEY, OF BEVERLY, MASSACHUSETTS, ASSIGNOR TO UNITED SHOE MACHINERY CORPORATION, OF PATERSON, NEW JERSEY, A CORPORATION OF NEW JERSEY.

NAILING-DIE.

1,322,509.

Specification of Letters Patent. Patented Nov. 25, 1919.

Application filed January 28, 1918. Serial No. 214,173.

To all whom it may concern:

Be it known that I, FRED R. AKERLEY, a citizen of the United States, residing at Beverly, in the county of Essex and State of Massachusetts, have invented certain Improvements in Nailing-Dies, of which the following description, in connection with the accompanying drawings, is a specification, like reference characters on the drawings 10 indicating like parts in the several figures.

This invention relates to nailing dies and particularly to the form of die used in power nailing machines in which the nails are deposited in holes in the die from which they 15 are driven by power actuated nail drivers.

Nailing dies of this character are always used in machines for attaching heels to shoes, and difficulty has at times been experienced from the driver passages becoming clogged 20 by reason of the inadvertent introduction into a die of two loads of nails, or of the jamming in a driver passage of a nail and a splinter, or imperfect nail, or a broken driver. These materials not infrequently 25 become so tightly jammed in the driver passage that it is impossible to remove them with a punch, and it is then necessary to drill them out. Inasmuch as both the drivers and the nailing die are hardened, it is 30 usually impossible to perform this drilling operation, until after they have been annealed. The common practice under such circumstances is to send the die to the manufacturer of the machine to be annealed, 35 drilled out, rehardened, and returned. This, of course, involves expense and, what is more important, the loss of the use of the die for a substantial period of time. This condition is likely to occur at a time when 40 the use of the particular die is very necessary, and great annoyance and considerable loss often result.

The object of the present invention is to provide a nailing die which will not differ 45 in appearance nor function from the standard dies already in use, but which will be constructed to permit the machine operator easily and quickly to remedy the condition above outlined without any material expense 50 or loss of time.

With this object in view, an important feature of the invention consists in the provision, in a nailing die of a nail and driver guiding member or bushing, of sufficient 55 length to insure that any jamming or clog-

ging that may occur will take place within the said member, contained in a suitable chamber in the die and fitting loosely enough to permit it to be easily and quickly removed. The die is preferably constructed 60 in two sections, into one of which the bushing or guiding member is inserted while the other acts as a retainer to prevent displacement of said member. In the embodiment of the invention illustrated, in the accompanying 65 drawings and hereinafter specifically described, one section of the die is made thick and provided with a chamber extending nearly through it and with a coaxial smaller hole extending the remainder 70 of the way through, and having a diameter the same as that of the usual nail and driver conduit. The second section of the die is relatively thin but is otherwise constructed 75 similarly to the thick section. When these die sections are secured together with the holes in alignment, a chamber extending nearly through the die is formed. A cylindrical, tubular bushing fits loosely in this chamber and its central hole is of the same 80 diameter as, and in alignment with, the holes in the opposite faces of the die, so that when the device is assembled, there is a continuous hole of uniform diameter for guiding the drivers and nails, in the same way as in the 85 ordinary nailing die.

A nailing die constructed in accordance with the present invention has valuable advantages over those heretofore used. In the event of one of the nail passages becoming 90 clogged by the jamming of nails or drivers, the machine operator can very quickly remove the bushing retaining section of the die, pick out the tube which is clogged, replace it with a new tube, replace the retainer, and resume work with the machine. The device is very simple in construction 95 and inexpensive to manufacture and contains no complicated mechanism nor parts which might get out of order or interfere 100 with its ordinary, normal use. The nail and driver guiding tube or bushing is a simple, one-piece device which can be manufactured in quantities and very cheaply. Consequently, the expense of replacing a clogged 105 bushing is so insignificant that it may be almost disregarded, while the gain in convenience and saving of loss in being able to continue the use of the machine without interruption is a matter of great importance. 110

The drawing is a perspective view partly in section, illustrating a nailing die embodying my invention.

Referring now to the drawing, 10 indicates a thick die section of the same contour as the nailing die commonly used. A thinner section 12 of the same size and shape as the section 10 is located in register with the latter and secured thereto by any suitable, 10 easily detachable means, such, for example, as screws 14. The usual nail and driver guiding holes 16 are drilled in the die section 10, emerging from the outer face 18 thereof. The holes 16 are enlarged in the 15 interior of the die, forming chambers 20 of larger diameter than, but co-axial with, the holes at the surface 18. Similar holes 22 of the same size as, and in alinement with, the holes 16 are drilled in the thinner die section 12 and these holes are also enlarged in the 20 interior of the die section to form chambers 24 which, when the die is assembled, are continuations of the chambers 20. Thus, when the die is assembled, there is in 25 its interior a series of cylindrical chambers extending from points very close to one face of the die to points very close to the opposite face of the die, and these chambers are connected to the faces of the die by the alined holes 16, 22.

In each of the chambers is placed a one-piece, rigid, tubular nail and driver guiding member or bushing 26 which fits sufficiently loosely in the chamber to permit it 30 to be easily removed with the fingers, but, closely enough to cause it to be retained immovably in position when the two sections of the die are secured together. The guiding member or bushing 26 has through it an axial hole 28 of the same diameter as, and in alinement with, the holes 16 and 22. When the device is assembled, as shown, it 35 presents the usual series of nail and driver guiding holes or conduits of uniform size throughout and in actual use cannot be distinguished from the ordinary nailing die.

The bushings 26 are preferably made of hardened steel, and inasmuch as it is easier to harden a small part of this character than a thick, heavy piece of steel, such as a complete die, a device made according to 40 my invention may be even stronger and more durable than the ordinary hardened die. The die sections 10, 12 may be hardened or not, as desired, but ordinarily, they would be at least case-hardened to prevent 45 them from being bruised in handling.

In the drawing, two of the guiding members 26 are shown, one being in section, with 50 nails 30 and the upper ends of drivers 32 in them. This represents the relation of the parts when the die is used in a machine in which the nails are driven upwardly. The improved die, however, is equally applicable to a machine in which the nails are 55

driven downwardly by drivers descending from above, and one practical advantage of the construction illustrated is that the driver and nail guiding tubes are retained immovably in position so that it is impossible 70 for them to become displaced, however the die may be handled or whatever its position in the machine. This secure retention of the tubes is also of great importance in the event of drivers or nails becoming 75 jammed, whereupon great force is likely to be exerted upon the bushing, tending to move it lengthwise.

It will be perceived that the improved nailing die of my invention, while it is very 80 simple in construction and inexpensive to manufacture, offers great practical advantages in use over the nailing dies heretofore known, and these are not offset by any disadvantages resulting from the new construction.

Having described my invention, what I claim as new and desire to secure by Letters Patent of the United States is:—

1. A nailing die comprising two layers 90 secured together in contact with each other and having alined holes in opposite faces of the die, said holes being enlarged in the interior of the die to form a chamber, and a bushing fitting loosely in the chamber and 95 having a hole in alinement with those in the faces of the die.

2. A nailing die comprising a thick section having a large hole extending nearly through it and a co-axial smaller hole extending the remainder of the way through the section, a removable bushing fitting loosely in the large hole and having an axial hole in alinement with said smaller hole, and a relatively thin die section removably 105 secured to the thick section and acting to retain the bushing in place.

3. A nailing die having alined nail holes in its opposite faces and an enlarged chamber connecting said holes, and an easily removable bushing member in said chamber, said bushing being provided with a nail hole in alinement with those in the faces of the die and the parts being so proportioned that, when the bushing is in place, 110 there is a continuous hole of uniform diameter through the die.

4. A nailing die having holes of equal diameters in its opposite faces and an enlarged chamber connecting said holes, and 115 a tubular bushing fitting removably in said chamber, the hole through said bushing being in permanent alinement with the first mentioned holes when the bushing is in the chamber.

5. A nailing die containing a rigid, one piece, nail and driver guiding member extending through the greater part of the thickness of the die, and provided with means for normally retaining said member 120

in place in the die, said retaining means being readily detachable, to permit easy removal of the nail guiding member in the event of it becoming clogged with nails or 5 a broken driver.

6. A nailing die comprising a plurality of sections, means for separably securing said sections together, and a rigid, tubular, nail and driver guiding member contained

in the die, said member terminating adjacent to the opposite faces of the die and fitting sufficiently loosely to permit it to be readily removed when the die sections are separated.

In testimony whereof I have signed my 15 name to this specification.

FRED R. AKERLEY.
